UNITED STATES PATENT OFFICE.

ELIJAH ASHWORTH, OF MANCHESTER, ENGLAND.

GUIDE FOR CARD-SETTING MACHINES.

SPECIFICATION forming part of Letters Patent No. 621,988, dated March 28, 1899.

Application filed January 11, 1899. Serial No. 701,830. (No model.)

To all whom it may concern:

Be it known that I, ELIJAH ASHWORTH, machine-maker, a subject of the Queen of Great Britain and Ireland, of the Moss Brook 5 Works, Collyhurst, Manchester, in the county of Lancaster, England, and also of Fall River, Massachusetts, have invented a certain new and useful Improvement in Card-Setting Machines, (for which I have made an application 10 for patent in Great Britain, No. 15,261, dated the 12th day of July, 1898,) of which the following is a specification.

My said invention relates to improvements in card-setting machines for setting the card-teeth in the cloth foundation to produce card-filletting, as is well understood. In such machines the foundation is conducted between guide-wires provided with adjustable side stops to the feed-rollers which feed the foundation through the machines, the adjustable stops on the guide-wires serving to guide the foundation to the feed-rollers. It is found in practice that this method of feeding the foundation through the machine is subject to a 25 great disadvantage, inasmuch as the foundation is apt to deviate from a perfectly straight line in passing through the machine. Owing to such deviation or lateral movement of the foundation, it is impossible, without running 30 off the edge, to set the card-teeth close up to the edge of the foundation. It is customary, therefore, to adjust the card-setting arrangement so that a strip of fabric on either side is left void of teeth to allow for any lateral 35 movement of the cloth. Before the filleting, therefore, is wound upon the carding-engine cylinder the edges of the cloth foundation must be pared close to the teeth.

The object of my invention is to provide 40 means whereby the objectionable tendency to lateral movement of the foundation is overcome, so that I am enabled to set the card-teeth sufficiently near to the edges of the foundation to obviate the necessity of paring 45 the same.

The accompanying sheet of drawings more clearly illustrates my invention.

Figure 1 shows a front elevation of my improved means of guiding the card foundation 50 to the feed-rollers, together with so much of a card-setting machine as is necessary for the

comprehension of my invention. Fig. 2 is a sectional view at right angles to Fig. 1. Fig. 3 is a detail view of the strip c. Fig. 4 is a view of the guide-bracket, partly in section, 55 on the line X X, Fig. 1.

In carrying my invention into effect I provide a guide-bracket A, which I secure by bolts a a to the usual reciprocating carriage B. The bracket A is provided with an inclined channel or guide b, formed with turned-up edges b' b'. For varying widths of card foundation movable strips c of metal are employed, so that a space accurately coinciding with the width of foundation may be readily 60 obtained. As shown more particularly in Figs. 3 and 4, the metallic strip c is secured to the turned-up edge of the guide b by means of studs or pins d d, passing through holes bored in the turned-up edge b' and secured 65 by means of pinching-screws e e.

To adjust the guide accurately to the width of card foundation, the foundation is placed within the channel b. The pinching-screws e e are slackened, and the pins d d are slid in 70 their holes until the metallic strip c is brought to bear against the edge of the cloth foundation, the other edge of the foundation bearing against the other turned-up edge b' of the channel b. When the requisite adjustment 75 has been obtained, the strip c is secured by the screws e e.

When the foundation f has been arranged within the guide-channel b, a separate plate g is placed upon the foundation and secured 80 in position by means of a screw h, provided with a conical end engaging with a conical recess in the plate g, the screw being provided with a lock-nut i. The plates g are provided in varying sizes to correspond with 85 the varying widths of card foundation. The screw h is screwed through a cross-bar h', secured to the guide-bracket A. The confining or retaining plate g is adjusted to the thickness of the foundation f by means of the 90 screw h, being prevented from rising thereby, and beds close upon the foundation, permitting it to be drawn through the machine as required, but preventing any tendency of the foundation to rise. The sides b' of the guide 95 b also prevent the foundation from deviating in the slightest degree from a perfectly

straight line. By these means a channel is provided accurately corresponding to the width and thickness of the card foundation, as will be more apparent from an inspection 5 of Fig. 4.

The guide is disposed with its delivery end close up to the nip of the feed-rollers C C, so that immediately after the foundation is drawn from the guide it is gripped by the 10 feed-rollers. The guide-bracket A is provided with slots *j* for the securing-bolts *a*, so that it may be moved laterally to compensate for the wear of the parts used for effecting the lateral traverse of the carriage B.

15 By means of my improved guide the foundation is conducted in such a perfectly straight path that I am enabled to set the card-teeth close to the edge of the foundation, thus obviating the necessity for any paring 20 of the fabric. The cost of labor of such paring is thus saved, as well as resulting in economy of material, none of the foundation being cut to waste. Moreover, by using card foundation in which the various layers are 25 woven to the requisite width I am enabled

to preserve the selvages uncut, and the foundation is thus left solid to the edges.

I declare that what I claim is—

1. In combination with a card-setting machine a guide-bracket A formed with a channel *b*, retaining-plate *g* and means for adjusting the guide-channel to the width and thickness of foundation, for the purpose of guiding the card foundation to the feed-rollers substantially as described. 30

2. As means for guiding card foundation to the feed-rollers of card-setting machines, an attachment consisting of a guide-bracket formed with a channel, a movable metallic strip for varying widths of card foundation, 40 a loose retaining-plate, and means for adjusting the retaining-plate to varying thicknesses of foundation, substantially as described.

In witness whereof I have hereunto set my 45 hand in presence of two witnesses.

ELIJAH ASHWORTH.
